TORPEDO SIGNAL FOR RAILWAYS

Herbert L. Bone, Forest Hills, and Kenneth J. J. McGowan, Pittsburgh, Pa., assignors to The Union Switch and Signal Company, Swissvale, Pa., a corporation of Pennsylvania

Application May 14, 1943, Serial No. 486,973

17 Claims. (Cl. 246—211)

Our invention relates to torpedo signals for railways, and particularly to improvements in torpedo signals of the type described in Letters Patent of the United States No. 493,482, granted to H. F. Clark on March 14, 1893.

As is well known torpedo signals are generally used in conjunction with a fixed wayside visual signal at railroad intersections, drawbridges, sidings or the like, and they serve as a means to provide a supplemental audible warning to an engineman in the event that he overruns the visual signal while it is in its stop position.

One object of our invention is to provide an automatic torpedo signal in which the part which is adapted to be struck by car wheels to explode the torpedo has a relatively long lever arm, is relatively free from friction, and is capable of withstanding the relatively large impacts to which it is subjected in service.

Another object of our invention is to provide a torpedo signal in which the part of the signal adapted to be struck by car wheels to explode the torpedo comprises the cover for the signal.

Another object of our invention is to enable the signal cover to be elevated sufficiently high when in the firing position to cause all wheels striking it to crush the torpedo to a "paper thin" thickness, and when in the non-firing position to be lowered sufficiently low so that wheels which have become channeled by rolling upon the rails will not strike the cover.

Another object of our invention is to provide means for preventing unwanted firing of a torpedo in the event that a maintainer accidentally drops the cover while opening or closing it.

Another object of our invention is to equip the cover with antirattler means which biases the cover downwardly at all times both in its firing and non-firing positions, but which at the same time enables the cover to be readily swung open for inspection and to subsequently be closed without interference from the antirattler means.

A further object of our invention is to equip the signal with means for providing at a distant point a telltale indication when one of the torpedoes is fired.

According to our invention the signal includes a fixed support adapted for attachment directly to a track rail, and having pivotally attached thereto at the end farthest from the track rail a body assembly and an overlying cover. The body assembly is yieldably supported at the end nearest the rail by spring means under initial compression, and is provided with a longitudinally extending guideway which slidably receives

a firing anvil and a torpedo slide. The torpedo slide is operable by external power means between a clear position in which a U-shaped recess formed in the end nearest the rail aligns with a torpedo magazine formed in the body assembly, and a firing position in which the recess aligns vertically with a firing pin provided on the cover, and is operatively connected with the firing anvil by a lost motion connection which moves the anvil toward the rail to a position underneath the firing pin when the slide is moved to its firing position and away from the rail to a position in which the firing pin will clear the anvil when the slide is moved to its clear position. Movement of the slide to its clear position permits a torpedo to drop from the magazine onto the firing anvil within the opening in the slide, and when the slide is next moved to the firing position, the torpedo is moved to a position underneath the firing pin. The slide and the cover are interconnected by suitable cam means which raises the cover to prevent the firing pin from interfering with the movement of the torpedo to or away from the firing position by the slide. The parts are so proportioned that when the torpedo is in the firing position, the firing pin will rest on it and the cover will then be elevated above the top of the rail to a position in which any wheel striking it will crush the torpedo to a "paper thin" thickness, but that when the slide is in clear position, the cover will drop down to a non-firing position in which it will not be struck even by wheels which have become channeled by rolling upon the rails. The cover is constantly biased downwardly by antirattler means so constructed that it will not interfere with the closing of the cover after it is opened by a maintainer. The cover and the slide are interlocked by means which prevents opening or closing of the cover except when the slide is in its clear position. The signal also includes a contact which becomes closed when the cover is lowered below its firing position, and which may be used in connection with a circuit controller contact the position of which is dependent upon the position of the slide to provide a telltale indication at a remote point when a torpedo is fired, or when the slide is in its firing position and there is no torpedo in the slide.

50 Other objects and characteristic features of our invention will become apparent as the description proceeds.

We shall describe one form of torpedo signal embodying our invention, and shall then point out the novel features thereof in claims.

In the accompanying drawings, Fig. 1 is a top plan view showing a torpedo signal embodying our invention applied to a railway track rail in the intended manner together with other signaling apparatus commonly used in connection with the signal. Fig. 2 is a side view of the apparatus shown in Fig. 1. Fig. 3 is a top plan view on an enlarged scale of the torpedo signal shown in the preceding views, a part of the cover being broken away to show the internal construction. Fig. 4 is a vertical longitudinal sectional view of the signal as shown in Fig. 3. Fig. 5 is a sectional view taken substantially on the line V—V of Fig. 4. Fig. 6 is a view similar to Fig. 4 but showing the parts in the positions they occupy when the signal is ready to be fired. Figs. 7 and 8 are perspective views of the hanger 1 and rail clip 6 respectively forming part of the signal embodying our invention. Fig. 9 is a detail sectional view taken on the line IX—IX of Fig. 4. Figs. 10 and 11 are enlarged perspective views of the body assembly B and cover C forming part of the signal embodying our invention. Fig. 12 is an enlarged perspective view of the torpedo slide forming part of the signal embodying our invention. Fig. 13 is an enlarged top plan view of a contact mechanism D forming part of our torpedo signal. Fig. 14 is a side elevational view of the contact mechanism shown in Fig. 13 with the cover removed and a part of the casing broken away to better illustrate the construction of some of the parts. Fig. 15 is a sectional view taken on the line XV—XV of Fig. 16. Fig. 16 is a wiring diagram showing a control circuit for the signal.

Similar reference characters refer to similar parts in each of the several views.

Referring to the drawings, the torpedo signal embodying our invention is designated as a whole by the reference character A, and comprises in general a support 1 shown in Fig. 7, a body assembly B shown in Fig. 10 and a cover C shown in Fig. 11.

The support 1 may be secured to the outer side of one track rail 3 of a stretch of railway track between an adjacent pair of the usual crossties 4 in any suitable manner, but as here illustrated it is clamped to the rail 3 by means of hook bolts 5 and rail clamps 6. The hook bolts 5 extend with considerable clearance through holes 6b (see Fig. 3) formed in the rail clips and through vertical slots 1b (Figs. 5 and 7) formed in laterally extending vertically disposed wings 1a provided on the forward end of the support, and each bolt is provided at the outer side of the associated wing with a plate washer 1, a lock washer 8, and a clamping nut 9. The vertical slots 1b permit the signal to be raised or lowered so that it may be vertically adjusted to suit any height of rail, and to facilitate this adjustment saddles 10 are disposed in the slots 1b in engagement with the upper sides of the hook bolts and set screws 11 mounted in screw threaded holes 1c formed in the wings directly above the slots are screwed into engagement with the saddles. It will be obvious that by adjusting the set screws the vertical position of the apparatus with respect to the rail can be readily varied to suit it to any particular size of rail. After this adjustment has been made the set screws 11 may be locked in their adjusted positions by means of jam nuts 12 as is obvious.

The rail clips 6 may have any preferred construction but as best seen in Fig. 8, in the form

illustrated they each comprise a central portion 6a which hooks over the base flange of the rail, and which central portion is provided with the previously referred to hole 6b through which the associated hook bolt 5 passes. The rail clips are also each provided with two spaced parallel side portions 6c which extend under and engage the underside of the base flange of the rail, whereby when the clamping nuts 9 are tightened, the support is very firmly clamped in the desired position relative to the rail. It should be pointed out that the rail clips 6 may be made in different sizes each size of which is suitable for use with all rails falling within a predetermined range of sizes.

The body assembly B (Fig. 10) comprises an anvil base 15 secured by means of studs 17 to the underside of a body casting 18. The studs 17 pass through clearance holes formed in laterally extending lugs 18a on the body casting and are screwed into tapped holes formed in underlying lugs 15a on the anvil base. The body assembly is pivotally attached to the support 1 at its outer end by means of a pivot pin 19 mounted in laterally spaced upstanding arms 1d provided on the support 1. The inner end of the body assembly is resiliently supported on a coil spring 21, and is guided for vertical sliding movement by means of spaced confronting ears 1e (Fig. 7) formed on the confronting sides of the wings 1a of the support 1. The coil spring 21 is mounted in a cavity 1f in the support 1 which cavity maintains the spring in its proper vertical position. The ears 1e in addition to serving as vertical guides for the body assembly also overlie stop lugs 15b formed on the anvil base, and the parts are so proportioned that the spring 21 will bias the body assembly upwardly to the vertical position in which the stop lugs engage the undersides of the ears.

Formed in part in the underside of the body casting 18 and in part in the upper side of the anvil base 15 is a guideway 22 which slidably receives a torpedo slide 23 and a firing anvil 24. The torpedo slide is movable between an outer or clear position in which a horseshoe shaped opening 25 (see Fig. 12) provided in its inner end aligns with a torpedo magazine 26 provided in the body casting 18, and an inner or firing position in which the opening 25 aligns with a firing pin opening 27 provided in the body casting 18. The torpedo slide overlies the firing anvil and is operatively connected therewith by a lost motion connection comprising a vertical pin 28 extending through an opening 24a in the firing anvil and provided at its upper end with a head 28a disposed in a longitudinal slot 23a formed in the underside of the slide 23. The lower end of the pin 28 extends into and cooperates with a longitudinal guideway 15c in the anvil base 15. The parts are so proportioned that when the slide is moved to its clear position, the left-hand end of the slot 23a as viewed in Fig. 4 will engage the head 28a of the pin 28 and will act through the pin to move the firing anvil away from the rail to the position shown in Fig. 4 in which the inner end of the anvil is out of vertical alignment with the firing pin opening 27, but that when the slide is moved to its firing position, the right-hand end of the slot 23a will engage the head of the pin 28 and will act to move the firing anvil toward the rail to the position shown in Fig. 6 in which it underlies the firing pin opening 27. The torpedo magazine 26 as shown is of tubular

75 The torpedo magazine 26 as shown is of tubular

form, open from end to end, with its lower end slightly smaller in diameter than the remainder of the magazine, and having an outwardly flaring or beveled lower edge 26a. The upper end of the magazine is closed by a cap 26b. The torpedoes are placed in the magazine by removing the cap 26b, and are constantly biased downwardly by a compressed coil spring 26c which is inserted into the magazine between the cap and the upper torpedo to insure that the torpedoes will move out of the magazine into the opening 25 in the torpedo slide when the slide is moved to its clear position. It will be obvious that when a torpedo has dropped into the opening 25, movement of the slide to its firing position will move the torpedo to a position directly beneath the firing pin opening 27. Furthermore, when a torpedo has been moved to its firing position, if the slide is then moved to its clear position, the torpedo will be retained in the opening by virtue of the fact that the outer end of the opening is slightly narrower than the width of the torpedo, and the torpedo will therefore be moved out of alignment with the firing pin opening.

The cover C overlies the body assembly B and is pivotally mounted at its outer end on the pivot pin 19 through the medium of bushed depending lugs 30 disposed between the arms 1d and the opposite sides of the body casting bearing. The cover is guided vertically both by the lugs 30 and by finished surfaces 30a (Fig. 5) on the inside faces of the cover cooperating with other finished surfaces 18b on the outside faces of the body. The inner end of the cover is disposed contiguous to the outer side of the rail head in a position to be at times depressed by car wheels rolling along the rail 1, and carries a firing pin 45 which extends through the firing pin opening 27 in the body casting 18 for cooperation with the torpedo to be fired.

The parts are so proportioned that when the torpedo slide is in firing position with an unfired torpedo in the opening 25, the firing pin 45 will rest on top of the torpedo and the cover will then be elevated to the position shown in Fig. 6 in which any wheel of a car rolling along rail 1 will force the cover downwardly far enough to compress the torpedo to a "paper thin" thickness. When, however, the torpedo slide 23 is in its clear position, as shown in Fig. 4, the cover is then free to drop downwardly to the position in which a lip 18d formed in the inner end of the body assembly engages the underside of the cover, and the parts are further so proportioned that with the cover in this latter position it will be lowered below the top of the rail sufficiently far so that it will not be struck even by car wheels which have become rather severely channeled by rolling on the rails.

When the slide is in the firing position, and the firing pin is resting on the anvil, as will be the case after a torpedo has been fired, the cover will then be held in an intermediate position in which it may project a slight distance above the rail. In these positions of the parts, each wheel passing the signal may strike the cover and each time a wheel strikes the cover, the spring 21 will yield to prevent damage to the signal.

Inasmuch as the firing pin rests on the torpedo to be fired when the slide 23 is in its firing position, it will be obvious that it is necessary to elevate the cover while the torpedo is being moved to or away from the firing position. For this purpose, the cover is provided with depending cam lugs 31 having oppositely inclined cam

faces 31a on their lower ends which cooperate with correspondingly shaped cam faces 32a formed on upstanding cam lugs 32 provided on the slide 23. The cam lugs 31 and 32 are so disposed that they will be clear of each other in both extreme positions of the slide, but that the cover will be raised sufficiently high in the intermediate positions of the slide by engagement of the cams to permit a torpedo to move underneath the firing pin with some clearance.

The upstanding cam lugs 32 on the slide 23 are disposed in longitudinally extending slots 18c formed in the body casting 18, and cooperate with the ends of these slots to limit the movement of the slide to the desired clear position. Movement of the slide in the opposite direction is limited by a shoulder 33 formed on the slide adjacent its outer end, which shoulder cooperates with a stop shoulder 34 formed on the underside of the body as shown in Fig. 6. These stops are so dimensioned that the firing pin 45 is just prevented from striking the inner edge of the torpedo opening 25 in the slide 23 when the slide occupies its firing position, and that only a very slight amount of movement of the opening 25 beyond the position where it aligns vertically with the torpedo magazine is permitted.

To prevent wear and to otherwise improve the operation of the signal it is necessary to eliminate vibration of the cover when it occupies both its firing and non-firing positions. We accomplish this result by providing the cover with anti-rattler means comprising a roller bracket 35 pivotally mounted on a hasp bolt 36. The hasp bolt 36 extends through aligned openings 18f formed in the opposite side walls of the body casting 18, and is provided at one end with a U-shaped return bend 36a the short leg of which extends into a shallow opening 18g formed in the one side wall of the casting 18 vertically below the associated opening 18f, whereby the bolt is maintained with the return bend in a vertical position for a purpose which will appear presently. The other end of the hasp bolt is threaded for the reception of a nut 37. The roller bracket is formed with spaced side portions 35a connected by a web 35b. The side portions 35a are provided at their lower ends with bosses 35c through which the hasp bolt 36 passes and which cooperates with bosses 18h on the body casting to position the bracket 35 centrally of the body casting. A roller 37 is rotatably supported on a bolt 38 between the upper ends of the spaced side portions 35a of the bracket 35, and cooperates with a thrust member 39 riveted to the underside of the cover. A compressed coil spring is interposed between a spring guide 18j formed on the body casting and a similar guide 35d formed on the web 35b of the roller bracket, and this spring 60 constantly biases the roller bracket in a counter-clockwise direction as viewed in Fig. 4 to the position in which stops 35e formed in the forward edges of the side portions 35a of the bracket 35 engage the outer side of the torpedo magazine 65 26. The lower end of the thrust member 39 is curved in such manner that when the cover C is in either its firing or non-firing position, the reaction between the cover and the thrust member will exert a downward vertical force component 70 on the cover sufficient to prevent rattling but that the cover can be readily lifted upwardly in opposition to this component by a maintainer. The extreme lower end of the thrust member is curved in the opposite direction to that part which the 75 roller normally engages and this latter curvature

is such that when the cover is lowered after being raised, this lower part will automatically force the roller out of the way, and thus prevent the antirattle means from interfering with the closing of the cover.

The signal further includes means to provide protection against accidental firing of a torpedo by dropping of the cover while a maintainer is opening or closing the cover. This means comprises a cover hasp interlock shown in Fig. 5. Referring to Fig. 5, the cover is provided with a side lug 40 disposed vertically above the eye formed by the U-shaped return bend 36a of the hasp bolt. This lug and the eye cooperate with a slot 41 formed in the vertical arm 42a of a hasp 42. The hasp 42 is pivotally attached at 43 to the side of the body casting 18, and is provided in addition to the vertical arm 42a with a horizontal arm 42b which is disposed within a transverse recess 18m in the inside of the body casting 18 and which carries an upstanding interlocking pin 46. The pin 46 extends upwardly through a vertical opening 18n in the body casting 18 and cooperates at its upper end with an elongated recess 44 machined into the underside of the slide 23. A coil spring 42c is interposed between the upper side of the horizontal arm 42b and a recess 18p formed in the underside of the body casting, and constantly biases the hasp in a counterclockwise direction as viewed in Fig. 5 to an extreme position in which the slot 41 in the vertical arm 41a receives the lug 40 and eye 36a. The parts are so proportioned that when the hasp occupies its counterclockwise extreme position, a padlock may be inserted through the eye formed by the U-shaped return bend 36a to lock the hasp in this position. In this position of the hasp, the lug 40 cooperates with the upper end of the slot 41 to prevent the cover from being raised above the firing position. When it is desired to raise the cover above the firing position to inspect the signal, it is necessary to remove the padlock and rotate the hasp in a clockwise direction as viewed in Fig. 5 to a position in which the lug 40 can clear the upper end of the slot. The parts are so proportioned that the hasp can only be rotated to this latter position when the pin 46 is free to enter the recess 44 in the slide 23, and that the recess 44 will only align with the pin when the slide bar has been moved far enough toward its clear position to withdraw the torpedo from underneath the firing pin 45. When the cover has been raised and the hasp 42 is released, the spring 42c acts to immediately restore the hasp to the position shown in Fig. 5 in which position the pin 46 is withdrawn from the recess 44. With the parts in these latter positions, the slide can be readily moved between its clear and firing positions for inspection or adjustment. If an attempt is made to lower the cover without first rotating the hasp to the position in which the pin 46 enters the recess 44 in the slide 23 the lug 40 will strike a horizontal shoulder formed on the upper end of the arm 42a and prevent the cover from being lowered far enough to permit the firing pin to accidentally fire a torpedo. It will be seen, therefore, that it is necessary for the slide to be in the clear position in order to lower the cover to its closed position as well as to open the cover. The padlock hasp 36a serves as a means to preclude anyone but an authorized person from opening the cover.

The slide 23 may be moved between its clear and firing positions by any suitable means. As

illustrated in Fig. 1, it is connected by a link 50 and adjustable screw jaw 51 with the piston rod 52 of a fluid pressure motor 53. The fluid pressure motor forms no part of our present invention, and is of conventional construction being provided with ports at both ends of the cylinder so that it is double acting. The supply of fluid pressure to the motor is controlled by a suitable valve mechanism V also of standard construction, including a normal magnet N effective when energized to admit fluid to the right-hand end of the motor to thereby move the piston rod out of the cylinder to its projected position and thus move the slide from its clear to its firing position, and a reverse magnet R effective when energized to admit fluid to the opposite end of the cylinder to move the piston rod into the cylinder to its retracted position and thus move the torpedo slide to its clear position.

Associated with the fluid pressure motor 53 is a circuit controller 54, which may for example be similar to that described and claimed in Letters Patent of the United States No. 2,190,520, granted on February 13, 1940, to Edwin G. Little. This circuit controller is provided with an operating shaft 55 connected by a crank 56 and an adjustable link 57 to the piston rod 52 of the fluid pressure motor 53, and includes a plurality of contacts each controlled by a different cam, the cams being individually adjustable to enable the contacts to become open or closed at any desired position in the stroke of the slide. These contacts may be used to control visible signals for indicating the condition of the torpedo signal in a manner which will be described presently, or for any other desired purpose. The wires leading to and from the circuit controller are carried through a sheathed conduit 57 to a junction box 58, which latter is shown connected with a parkway cable 59 and also with another sheathed conduit 57a leading to the valve mechanism V.

It is desirable to be able to indicate at a remote point, such as an interlocking tower, when a train fires a torpedo, to enable the particular train which operated the signal to be identified. For this purpose we have provided the signal with a contact mechanism which is intended to be used in conjunction with one of the contacts of the circuit controller 54 as will be made clear presently. This contact mechanism also provides a means for indicating that the slide is in its firing position and there is no torpedo in the slide.

This contact mechanism is arranged to be bolted to the side of the main body casting 18, and is designated as a whole by the reference character D. As best seen in Figs. 13, 14 and 15, this circuit controller comprises an auxiliary housing 60 closed by a removable cover 61. Disposed within the housing 60 is a fixed contact finger 62 and a cooperating movable contact finger 63 secured respectively to contact supports 64 and 65. The supports 64 and 65 are insulated from the housing 60, but are electrically connected with terminal posts 66 and 67, whereby external electrical connections with the contact fingers may be readily made. The movable finger 63 is provided at its upper end with a curved actuating member 63a which cooperates with an insulating contact operating cam 68 secured to the lower end of an operating plunger 69. The plunger 69 is slidably mounted in bushings 70 disposed in a vertical opening 71 formed in the housing 60, and is constantly biased to an upper position by means of a compressed coil

spring 72 disposed in the housing 60 between the cam 68 and a plug 73 which closes the lower end of the opening 71. The upper end of the plunger 69 cooperates with a screw 74 adjustably mounted on a lateral extension 75 formed on the cover. The extension 75 serves to protect the contact mechanism from ice and snow, and includes an annular portion 75a which surrounds the upper end of a tubular portion of the housing 68 through which tubular portion the upper end of the plunger 69 extends. As shown the parts are so arranged that when the plunger 69 is moved to its upper position by the spring 72, the cam 68 will engage the curved end of the movable finger 63 and force it into engagement with the fixed finger 62 to close the contact 62-63, and the screw 74 is so adjusted that when the cover is in its "ready to fire" position with the firing pin 45 resting on top of a torpedo, the screw 74 will engage the upper end of the plunger and depress it slightly but not enough to open the contact. It will be obvious, therefore, that when a torpedo is fired, the downward movement of the cover which caused the torpedo to become fired will act through the screw 74 to depress the plunger and when this happens, the cam 68 will move out of engagement with the contact finger 63. The finger 63 is biased by its own resiliency to a position in which it is out of engagement with the fixed finger 62, and it follows that the movement of the cover to its lowermost position will cause the contact 63-62 to open.

It should be made clear that while the contact 63-62 is arranged as a normally closed contact, this contact could equally well be arranged as a normally open contact as is obvious.

Inasmuch as the cover C is free to move to its lowermost position both when a torpedo becomes fired and when the slide 23 is moved to its clear position, it is necessary in order to distinguish between the clear and fired positions of the torpedo machine to employ a contact of the circuit controller 54 in conjunction with the contact 63-62 to provide an indication at a remote point of the firing of a torpedo. One circuit arrangement for accomplishing this result is shown in Fig. 16 wherein the contact of the circuit controller 54 is designated 76-77 and is so adjusted that this contact will be closed when the torpedo slide is in the clear position and will remain closed when the slide is moved toward the firing position until after the cooperating cam lugs 31 and 32 have lifted the cover C to its upper position. The contacts 63-62 and 76-77 are connected in parallel in a pick-up and stick circuit for an indication relay R. The pick-up circuit also includes a push button P and passes from a suitable source of current here shown as a battery X through wires 80 and 81, the contacts 63-62 and 76-77 in parallel, wires 82 and 83, push button P, and the winding of relay R back to battery X. When this circuit becomes closed, relay R picks up and closes its stick circuit which passes from battery X through wires 80 and 81, the contacts 62-63 and 76-77 in multiple, wire 82, front contact 84 of relay R, and the winding of relay R back to battery X. Once the stick circuit for relay R becomes closed, relay R will remain energized until the contacts 62-63 and 76-77 both become simultaneously opened. This will happen when and only when the slide is in the firing position and a torpedo becomes fired or there is no torpedo in place in the slide for some other reason.

The relay R may be used to control a visible or audible signal or both. As shown, it is arranged to control a lamp L and a buzzer E both of which are connected in parallel in a control circuit which includes battery X and back contact 85 of relay R. It follows that when relay R becomes deenergized and closes its back contact, lamp L will become lighted to give a visible indication that a torpedo has been fired, and buzzer E will operate to give an audible indication. The lamp L will remain lighted and buzzer E will continue to operate until one or the other or both of the contacts 63-62 or 76-77 becomes closed and push button P is operated while such contact or contacts are closed. To cause this to happen, it is necessary for the torpedo slide to be returned to its clear position.

Although we have herein shown and described only one form of torpedo signal for railways embodying our invention, it is understood that various changes and modifications may be made therein within the scope of the appended claims without departing from the spirit and scope of our invention.

Having thus described our invention, what we claim is:

1. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, and means for elevating said cover while said slide is being moved to or away from its firing position.
2. The combination in a torpedo signal in which a torpedo is moved between a firing and a non-firing position by a torpedo slide and is arranged to be fired by a firing pin secured to a depressible member for the signal, of means to permit the member to be raised above the rail sufficiently far when the slide is in its firing position to insure that the torpedo will be crushed to a "paper thin" thickness if a wheel depresses the member and to be lowered sufficiently far below the rail when the slide is in its non-firing position to prevent the member from being depressed by wheels which have become channeled, said means comprising a firing anvil disposed underneath the slide and connected therewith by a lost motion connection which moves the anvil underneath the firing pin or withdraws it from beneath the firing pin according as said slide occupies its firing or its clear position.
3. A torpedo signal comprising a support secured to a track rail at the outer side of the rail,

a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover while said slide is being moved to or away from its firing position, and means to prevent said cover from being manually opened except when said slide is moved away from the firing position.

4. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover while said slide is being moved to or away from its firing position, and means interlocking said cover and said slide and effective to prevent opening of said cover by a maintainer except when said slide is moved away from the firing position.

5. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said

torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover while said slide is being moved to or away from its firing position, and means to prevent said cover from vibrating.

6. A torpedo signal comprising a support secured to a track rail at the outer side of the rail, 15 a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a 20 torpedo slide slidably mounted in said body member for movement between clear and firing positions and provided in its inner end with a torpedo opening which aligns vertically with said torpedo magazine or said firing pin according as 25 said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover while said slide is being moved to or away from its firing position, and antirattler means to prevent said cover 30 from vibrating comprising a roller bracket pivotally attached to said body assembly and biased to one position, a roller mounted in said bracket, and a thrust member secured to said cover for cooperation with said roller, said thrust member 35 being curved in such manner that the reaction between said thrust member and said roller due to the biasing force will exert a downward force component on said cover sufficient to prevent rattling but that the cover can be readily raised above its firing position in opposition to this force by a maintainer and subsequently lowered into position without interference by said antirattler means.

7. A torpedo signal comprising a support secured to a track rail at the outer side of the rail, 35 a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below 40 the top of the rail, a firing pin secured to said cover, a torpedo slide slidably mounted in said body member for movement between clear and firing positions and provided in its inner end with a torpedo opening which aligns vertically with said torpedo magazine or said firing pin according as 45 said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, and antirattler means to prevent said cover 50 from vibrating comprising a roller bracket pivotally attached to said body assembly and biased to one position, a roller mounted in said bracket, and a thrust member secured to said cover for cooperation with said roller, said thrust member 55 being curved in such manner that the reaction between said thrust member and said roller due to the biasing force will exert a downward force component on said cover sufficient to prevent rattling but that the cover can be readily raised above its firing position in opposition to this force by a maintainer and subsequently lowered into position without interference by said antirattler means.

firing pin to permit the cover to drop to its non-firing position according as said slide is moved to its clear or firing position, and means for elevating said cover while said slide is being moved to or away from its firing position, the parts being so proportioned that when a torpedo becomes fired and causes said pin to rest on said anvil said cover will occupy an intermediate position in which it may be engaged by car wheels, said resilient support serving as a yielding means to prevent damage to said signal when said firing pin is resting on said anvil and said cover is depressed.

8. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, and means for elevating said cover while said slide is being moved to or away from its firing position comprising cam lugs on said slide cooperating with cam lugs on said cover.

9. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, and means for elevating said cover while said slide is being moved to or away from its firing position comprising cam lugs on said slide cooperating with cam lugs on said cover, said cam lugs on said slide being disposed in slots in said body assembly and cooperating with the ends of said slots to limit the movement of said slide to its clear position.

10. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover while said slide is being moved to or away from its firing position comprising cam lugs on said slide cooperating with cam lugs on said cover, said cam lugs on said slide being disposed in slots in said body assembly and cooperating with the ends of said slots to limit the movement of said slide to its clear position, and a stop shoulder formed on said slide and cooperating with a stop shoulder on said body assembly to arrest the movement of said slide when it reaches its firing position.

11. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover while said slide is being moved to or away from its firing position, a contact secured to said body assembly, and adjustable means for operating said contact when said cover is lowered a predetermined distance below its firing position.

12. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for move-

ment between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover while said slide is being moved to or away from its firing position, a contact comprising a fixed contact finger and an associated movable contact finger, said contact fingers being secured to said body assembly in cooperating relation but insulated therefrom, a plunger secured to said body assembly and biased to an upper position, a cam secured to said plunger and cooperating with said movable contact finger for operating said contact when said plunger becomes depressed, and means for depressing said plunger when said cover is lowered a predetermined distance below its firing position comprising a set screw adjustably mounted on said cover.

13. In a torpedo signal including a cover which is depressed by a car wheel to fire a torpedo and a slide which is movable from a clear to a firing position to place the torpedo in position to be fired by depression of the cover, the combination of a circuit controller operatively connected with the slide and provided with a first contact which becomes closed when the slide occupies its clear position and opened when the slide occupies its firing position, a second contact which becomes opened when said cover is depressed to fire a torpedo, a relay, a pick-up circuit for said relay including a normally open manually operable push button and said two contacts in multiple, a stick circuit for said relay including its own front contact and said first and second contacts in multiple, and indication means controlled by said relay.

14. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position, a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover

while said slide is being moved to or away from its firing position, and means to prevent said cover from being manually opened or closed except when said slide is moved away from the firing position comprising a hasp pivotally attached to the body assembly and provided with a vertical arm and a horizontal arm, said vertical arm being provided with a slot, an eye secured to said body assembly in a position to enter said slot 5 when said hasp is rotated to one position, a lug on said cover disposed to enter said slot when said hasp is rotated to said one position and to move clear of said slot if said cover is raised when said hasp is rotated to another position, 10 said lug being effective when in said slot to prevent said cover from being manually opened, means for biasing said hasp to its one position, and a pin carried by said vertical arm and co-operating with a slot in said slide, the parts being so proportioned that said slide slot will align with said pin when and only when said slide is moved away from its firing position and that said hasp can only be rotated to its other position 15 when said slot aligns with said pin.

16. In a torpedo signal including a cover which is depressed by a car wheel to fire a torpedo through the medium of a firing pin secured to the cover, and a slide which is movable from a clear to a firing position to place the torpedo in position to be fired by depression of the cover, the combination of a firing anvil operatively connected with said slide and movable to a position below the firing pin or to a position in which it is withdrawn from beneath the firing pin according 20 as said slide occupies its clear or firing position, whereby said cover is permitted to drop a sufficient amount to insure that it will not be engaged by car wheels when said slide is in its non-firing position.

17. A torpedo signal comprising a body member attached to one side of a track rail and provided with a magazine containing torpedoes and with means for moving the torpedoes to or away from firing positions, and a cover pivotally attached to 25 and overlying said body member and movable between an upper position in which it will be depressed by car wheels traversing said rail and a lower position in which car wheels traversing said rail will clear said cover, said cover being provided with a firing pin which cooperates with a torpedo in the firing position when said cover is depressed to explode such torpedo, and means for permitting said cover to be manually raised to gain access to said body member when and only 30 when all of said torpedoes are in non-firing positions.

18. A torpedo signal comprising a support secured to a track rail at the outer side of the rail, a body assembly pivotally attached to the outer end of said support and resiliently supported at the end nearest the rail by spring means mounted in said support, a torpedo magazine formed in said body assembly, a cover pivotally attached to said support above said body assembly for movement between a firing position in which the cover is disposed above the top of the rail and a non-firing position in which it is disposed below the top of the rail, a firing pin secured to said cover, a torpedo slide slidably mounted in said body member for movement between clear and firing positions and provided in its inner end with a torpedo opening which aligns vertically with said torpedo magazine or said firing pin according as said slide occupies its clear or its firing position,

a firing anvil secured to said slide below said torpedo opening by a lost motion connection which moves the said anvil underneath the firing pin or removes it from beneath the firing pin to permit the cover to drop to its non-firing position according as said slide is moved to its clear or firing position, means for elevating said cover

5 while said slide is being moved to or away from its firing position, and means to prevent said cover from being manually opened or closed except when said slide is moved away from the firing position.
